CLAIM

The ornamental design for a combined flexible sensor array and sensors, substantially as shown and described.

DESCRIPTION

FIG. 1 is a perspective view of a combined flexible sensor array and sensors.

FIG. 2 is a front view of the sensor of FIG. 1.

FIG. 3 is a rear view of the sensor of FIG. 1.

FIG. 4 is a right-hand-side view of the sensor of FIG. 1.

FIG. 5 is a left-hand-side view of the sensor of FIG. 1.

FIG. 6 is a top view of the sensor of FIG. 1; and,

FIG. 7 is a bottom view of the sensor of FIG. 1.

The broken lines show portions of a combined flexible sensor array and sensors that form no part of the claimed design.
